CIRCUIT ARRANGEMENT FOR COMPENSATING THE AERIAL EFFECT OF DIRECTIONAL ANTENNAE

Theodoor Willem La Riviere, Eindhoven, Netherlands, assignor, by mesne assignments, to Hartford National Bank and Trust Company, Hartford, Conn., as trustee

Application May 1, 1946, Serial No. 666,249
In the Netherlands November 20, 1941

Section 1, Public Law 690, August 8, 1946
Patent expires November 20, 1961

5 Claims. (Cl. 343—113)

1

It has been suggested before to compensate the aerial effect of directional antennae by means of a compensation signal received in a non-directional manner and combined in the correct phase with the signal received in a directional manner.

With direction-finding receivers having directional antennae the measuring instruments and operating members are frequently arranged at a distance from the receiver proper so that it is also necessary for the above-mentioned compensation to be adjusted from a distance.

The invention has for its object to provide a circuit arrangement of the above-mentioned kind capable of being adjusted in a simple manner, in some cases from a distance.

According to the invention, the compensation signal is fed, with the interposition of a phase-shifting network, to a control electrode of a discharge tube having at least two output electrodes, the circuits of the output electrodes being coupled in opposite senses to an impedance to which the signal received in a directional manner is supplied in push-pull and from which the desired signal is derived, the current distribution between the two output electrodes being variable by variation of the bias voltage of one or more electrodes of the discharge tube.

In order that the invention may be clearly understood and readily carried into effect it will now be described more fully with reference to the accompanying drawing, in which one embodiment is illustrated.

Fig. 1 is the schematic diagram of a first preferred embodiment of the invention, and Fig. 2 illustrates a modification in the arrangement of Fig. 1.

Referring to the Figure 1 of the drawing, a rotatable loop antenna 1 is connected to the ends 2 and 4 of the primary of the input transformer of a receiver 5. The mid-point tapping 3 of the primary is earthed with the interposition of a condenser 6. Owing to the aerial effect of the loop antenna 1 the voltage supplied to the primary is not entirely equal to zero when the frame is arranged normally to the direction of incidence of the signal. The direction of incidence of the signal is thus ascertained with greater difficulty.

In order to obviate the difficulty the primary has supplied to it a compensation signal which is received by means of a non-directional antenna 7. The antenna 7 is connected to earth via a resistance 8.

According to the invention, the voltage existing across the resistance 8 is supplied to a con-

2

trol electrode of a pentode 11 with the interposition of a phase-shifting network 9, 10.

The phase-shifting network comprises a resistance 9 and a condenser 10, the resistance being large compared with the impedance of the condenser so that the network brings about a phase-displacement of about 90°.

The pentode 11 comprises a cathode 12, a control grid 13, a screen grid 14, a suppressor grid 15 and an anode 16. The voltage existing across the condenser 10 is supplied to the control grid 13. The cathode lead of the tube 11 includes the parallel combination of a resistance 17 and a condenser 18 which serves to generate the required negative bias.

The screen grid 14 is connected to the end 4 and the anode 16 to the end 2 of the primary of the input transformer. The requisite positive bias for the anode and the screen grid is supplied through the mid-point tapping 3 via a resistance 19.

The suppressor grid 15 has supplied to it, through a conductor 20, a variable bias by means of which the compensation can be adjusted.

The non-directional antenna 7 may be used at the same time for ascertaining the sense and for this purpose is connected to the receiver through a conductor 21.

The operation of the circuit arrangement described is as follows. The anode current of the tube 11 brings about an alternating voltage across the top portion of the primary of the input transformer, which portion is comprised between the terminals 2 and 3. Similarly, the screen grid current brings about an alternating voltage across the bottom portion of the primary, which portion is comprised between the terminals 3 and 4. The two alternating voltages mentioned are directed in opposite senses. Thus, if the bias of the suppressor grid 15 is so adjusted that the anode current is equally large as the screen grid current the two alternating voltages mentioned will neutralise each other so that no compensation is effected at all. If the suppressor grid is made more positive the anode current will preponderate over the screen grid current so that a resulting compensation voltage of given phase is set up across the primary. Variation of the bias of the suppressor grid 15 therefore permits of regulating the value and the polarity of the compensation voltage existing in the primary so that full compensation of the aerial effect can be achieved at any time. The bias of the suppressor grid 15 can be adjusted in a simple manner from

55

a distance with the aid of a potentiometer located near the operator.

Instead of having connected to them the rotatable loop antenna 1 the ends 2 and 4 of the primary of the input transformer may have connected to them a searching coil which is coupled with two fixed directional antennae, for example the two loops set at right angles to each other.

This is illustrated in Fig. 2 which shows two perpendicularly arranged loop antennas 22 and 23 connected to the crossed field coils 24 and 25 of a conventional goniometer 26 whose search coil 27 is connected to the primary of the input transformer of receiver 5. The circuit is otherwise identical with that of Fig. 1.

I claim:

1. In a direction finding system having a directional antenna coupled across the input impedance of a radio receiver, an arrangement to compensate for aerial effect in said directional antenna comprising an amplifier circuit including an electron discharge device having a control electrode and two output electrodes, one of said output electrodes being coupled to one end of said impedance and the other output electrode being coupled to the other end of said impedance whereby the currents flowing at the two output electrodes are applied to the impedance in opposing senses, a non-directional antenna, a phase shifting network, means to impress signals derived from said non-directional antenna through said network onto said control electrode, and means to vary the current distribution between the two output electrodes.

2. In a direction finding system having a directional antenna coupled across the input impedance of a radio receiver and a sense antenna coupled to said receiver, an arrangement to compensate for aerial effect in said directional antenna comprising an amplifier circuit including an electron discharge device having a control electrode and two output electrodes, one of said output electrodes being coupled to one end of said impedance and the other output electrode being coupled to the other end of said impedance whereby the currents flowing at the two output electrodes are applied to the impedance in opposing senses, a phase shifting network, means to impress signals derived from the sense antenna through said network onto said control electrode, and means to vary the current distribution between the two output electrodes.

3. In a direction finding system having a pair of crossed directional antennae connected to the field coils of a goniometer, the search coil of the goniometer being connected across the primary of the input transformer of a radio receiver, an arrangement to compensate for aerial effect in said directional antennae comprising an amplifier circuit including an electron discharge device having a control electrode and two output electrodes, one of said output electrodes being connected to one end of said primary and the other of said output electrodes being connected to the other end of said primary whereby the output currents flowing at the two output electrodes

are applied to said primary in opposing senses, a non-directional antenna, a phase shifting network, means to impress signals derived from said omni-directional antenna through said network onto said control electrodes, and means to vary the current distribution between the two output electrodes.

4. In a direction finding system having a directional antenna coupled across the center-tapped input impedance of a radio receiver, an arrangement to compensate for aerial effect in said directional antenna comprising an amplifier circuit including an electron discharge tube having a cathode, a control grid, a screen grid, a suppressor grid and an anode, said screen grid being connected to one end of the input impedance and said anode being connected to the other end thereof, means to apply a positive potential to the centertap of the impedance to energize said tube, means to apply an adjustable negative bias to said suppressor grid to vary thereby the current distribution between said screen grid and said anode, a non-directional antenna, a phase-shifting network, and means to impress signals derived from said non-directional antenna through said network onto said control grid.

5. In a direction finding system having a directional antenna coupled across a center-tapped input impedance of a radio receiver, an arrangement to compensate for aerial effect in said directional antenna comprising an amplifier circuit including an electron discharge device having a cathode, a control grid, a screen grid, a suppressor grid and an anode, said screen grid being connected to one end of said impedance, said anode being connected to the other end of said impedance, a cathode biasing resistor, a source of direct potential having its positive terminal connected to the centertap of said impedance and its negative terminal connected through said resistor to said cathode thereby to energize said device, means to apply an adjustable negative bias to said suppressor grid to vary thereby the current distribution between said screen grid and anode, a non-directional antenna, and a 90° phase shifting network constituted by a resistance in series with a capacitance, the free end of said resistance being connected to said non-directional antenna and the free end of said capacitance being connected to the negative terminal of said source, the junction of said series-connected resistance and capacitance being connected to said control grid.
